UNITED STATES PATENT OFFICE.

HENRY L. DOHERTY, OF NEW YORK, N. Y.

PROCESS FOR MAKING PRODUCER GAS.

Application filed September 8, 1920. Serial No. 408,871.

This invention relates to a process for making producer gas and more particularly to the operation of gravity feed gas producers for burning inferior grades of soft coal.

Most of the gas producers in use at the present time consist of a vertical shaft for supporting a column of fuel and mechanism for burning the coal by a blast of air forced through the fuel under pressure. Some of the producers in use operate at such high temperatures that the ash of the coal is formed into and withdrawn from the producer as slag. Other producers do not operate at the high temperatures of slagging producers but the temperatures are sufficiently high to form large clinkers which are very difficult to remove from the producers. With both the slagging and clinker-forming producers, the slag and clinkers accumulate so that the producers have to be periodically cleaned. The accumulation of slag and clinker and any intermittent operation of the producers tend to produce substantial variations in the quality of the gas being made.

The primary object of the present invention is to provide a process of making producer gas by which a uniform quality of gas may be continuously produced without the objections above referred to.

Another object of the invention is to provide for the continuous operation of a gravity feed gas producer without the formation of clinkers.

Another object of the invention is to provide for the efficient operation of a gravity feed gas producer with an induced draft.

With these and other objects in view, the invention consists in the process of making producer gas hereinafter described and particularly defined in the claims.

The various features of the invention are illustrated in the accompanying drawings in which,

Figure 1 is a view in front elevation of a gravity feed gas producer embodying the preferred form of the invention;

Fig. 2 is a view in side elevation of the gas producer shown in Fig. 1;

Fig. 3 is a view of the gas producer in horizontal section taken on the line 3—3 of Fig. 2; and

Fig. 4 is a detail view in perspective illustrating the fuel-distributors, the vertical grates, and the device associated with the

grates for returning fuel back into the producer which has passed through the grates.

The preferred form of the invention embodies a gas producer of the type which is adapted to make gas for direct consumption in heating steam boilers. The gas producer illustrated in the drawings may be properly called a double producer in that two distinct vertical columns of fuel flow by gravity downwardly through the producer and the apparatus for treating the fuel to make gas is the same in each column. The producer proper consists of a vertical rectangular shaft which is supported in a structural steel framework (see Figs. 1 and 2). The front wall 10 and rear wall 12 are made of a fire-resistant masonry construction and the major portion of the upright longitudinal sides of the producer shaft consists of vertical open grates 14. The fuel burned in the producer, which usually consists of an inferior grade of soft coal, is held in a hopper 16 positioned on the top of the producer and flows from the hopper down through distributors 18 into the body portion of the producer. The distributors 18 extend along the full length of each side of the producer and discharge fuel into the producer immediately below an ignition fire arch 20 which constitutes the top of the producer. The fuel emerging from the distributors 18 spreads out toward the central portion of the producer along a dot and dash line 22, indicating the angle of repose of the fuel and is ignited by the aid of radiation from the arch 20.

The producer gas generated in the shaft is removed from the top of the fuel column through an opening 23 (the outline of which is shown by dotted line 21 in Fig. 1) formed in the rear wall 12 of the producer immediately below the fire arch 20. The producer gas formed in the producer passes upwardly throughout the length of the fuel column and preferably passes out of the producer while hot, directly into a combustion chamber to be burned.

The coal hopper 16 (Figs. 1 and 2) consists of a box-like structure which is supported upon and covers the top of the producer. The hopper is divided longitudinally into ten sections, there being five sections along each side of the producer, and the width of a section corresponds to the width of a distributor 18 (see Fig. 4). Each section has downwardly inclined sides 36 which

merge into a fuel chute 38 positioned in the upper end of the distributor 18. The hoppers are supported principally by the distributors 18 and the distributors 18 are supported upon I-beams 35 (Fig. 4) which extend longitudinally of the producer. When the producer is in normal operation, the fuel passes in a slow and substantially continuous stream from the hopper through the chutes 38 into the distributors 18. If, however, it becomes necessary to check or stop the operation of the producer, the flow of fuel from the hopper into the producer may be stopped by means of gates 40 which are pivoted to the opposite sides of the distributors 18 and arranged to swing under the open end of the chutes 38. To move the gates 40 into and out of position under chutes 38, a rack 42 is formed on the bottom of the gates the teeth of which mesh with pinions 44 fixed on shafts 46 journalled longitudinally of the distributors 18. The shafts 46 extend outwardly beyond the front end of the producer and may be manually operated by means of chains 50 which run over sprocket wheels 52. When the shafts 46 are rotated by the chains 50, all of the gates will be simultaneously moved to close or open the fuel chutes 38.

30 The air and other gases for controlling combustion of fuel in the producer are induced through the producer by an induced draft which preferably will consist of an induced draft fan located at the flue gas outlet of the steam boilers being heated. Since the fuel is quite open in the upper portion of the producer, the highest temperatures of combustion take place in the fuel as it advances from the distributor to the mid portion of the producer. At about the mid portion of the producer the fuel from the distributors 18 is divided into two columns and is supported on one side by the grates 14 and on the other side by inverted V-shaped grates 24 which extend the full length of the producer. By the time the fuel has advanced down to the upper portion of the V-shaped grates 24, the percentage of ash in the coal has increased and the bed is much thicker so that the resistance to the air for combustion is quite high, thus tending to lower the temperature resulting from combustion. As the fuel advances downwardly to a point where the percentage of ash is high enough to form a clinker with high temperature combustion, the ventilation is cut down to lower the temperatures below that at which the fuel containing ash will fuse. After the fuel moves down below the grates 14 and 24, it passes through cooling shafts 26 which are entirely surrounded by refractory walls so that any gases for controlling combustion in the shafts must enter through the bottom. The fuel emerging from the shafts 26 runs onto grates 28

which are spaced below the lower ends of the shafts 26 a considerable distance to allow the fuel to spread out and open up. The grates 28 are open and gaseous products of combustion, which consist of flue products from a boiler, are introduced through a conduit 30 and pass up through the grates 28 into the shafts 26. The flue products admitted from the conduit 30 act to cool fuel and ash in the shafts 26 by absorbing sensible heat and carrying it toward the upper portion of the fuel column. When the flue gas comes in contact with the hotter portions of the fuel column, the carbon dioxide will be dissociated with an endothermic reaction and the dissociation products will absorb heat from the fuel column and act to cool the mixture of fuel and ash in the column. In some cases it may be desirable to introduce flue gases through the grates 24 to control the temperature of fuel in the mid-portion of the producer immediately above the grates 24.

When burning coal producing some kinds of ash, especially if the ash content is high, it will be necessary to pass the fuel through the producer at such a rate that unburned carbonized fuel will be discharged from the bottom of the producer in order to prevent the formation of clinkers. With coals which are low in ash and other coals having a high ash content of a particular character, it may be desirable to pass the fuel through the shaft at such a rate that the coal or fuel will be entirely burned to ash before it is discharged from the bottom of the cooling shafts 26. With the coals having a low ash content, a slow rate of combustion may be maintained in the cooling shafts 26 to entirely burn fuel to ash before it reaches the bottom of the shafts. In this case, sufficient air is introduced with the return flue products entering through the conduit 30 to maintain a slow combustion in the shafts 26. To prevent the formation of clinkers when burning a coal having a high ash content, the grates 28 are arranged to be reciprocated to discharge the fuel emerging from the shafts 26 at such a rate that unburned carbonized fuel will be discharged from the grates to be collected in the hoppers 34. Any carbonized fuel collected in the hoppers 34 may be removed from the ash by screening and returned to the hopper 16 to be mixed with fresh fuel and again passed through the producer.

The capacity and efficiency of most boiler grates and gas producers depends directly upon the amount of coal which may be burned per square foot of grate surface. The vertical grates 14 which extend along the greater portion of the longitudinal sides of the fuel columns afford an enormous grate area for admitting the necessary air for supporting the combustion of the fuel.

The grate 14 consists of a series of vertical bars 54 (Figs. 1, 2 and 4) which extend between the lower end of the distributors 18 and the upper end of the cooling shafts 26. Slots 56 and 58 are formed in the ends of the bars 54 which are arranged to cooperate respectively with rods 60 mounted in the distributors 18 and ribs 62 formed on the upper face of a channel-beam 64 mounted along the sides of the gas producer frame. The slot 56 is sufficiently elongated so that the bar 54 may be raised vertically to clear the rib 62 and thus be removed from the side of the gas producer. When the bar 54 is in normal position, it will be held by gravity in contact with the rib 62 and thus prevented from becoming displaced. Although the grate bars 54 are shown as supported in a vertical position, this position is not essential since the bars may be supported in any inclined position at which the fuel on the grates will run by gravity.

The spacing of the grate bars 54 is important in that the spaces between the bars may be utilized for controlling the flow of air therethrough to control the rate of combustion. As the ash content of the fuel bed increases, the resistance to the passage of gases through the bed for controlling combustion increases. Accordingly, if the fuel bed is more open at the top than toward the bottom, it may be desirable to have the spaces between the grate bars at the bottom of the grates larger than the spaces between the bars at the top of the grates. Again, it may be desirable to maintain a slower rate of combustion in the lower portion of the fuel bed in which case the spaces between the grate bars at the bottom of the grates would be as small or smaller than the spaces between the bars at the top of the grates. To provide for these various factors, the bars may be made in any shape to give the desired ventilation area at different vertical levels of the grates.

Most of the coal used in gas producers is of an inferior grade and is often in the form of small granules. If the coal is a non-coking coal, such as lignite or anthracite, it will readily pass between the vertical bars of the grates 14 while burning. However, if the coal is a coking bituminous coal, it will tend to fuse to form coke when being heated in the upper portion of the producer, and there will not be such a great tendency for such fuel to run out between the grate bars. To prevent coal from running out of the producer through the grates, louvers 68 (Figs. 1, 2 and 4), are positioned in front of the grates in vertical rows with the inner edge of the louvers in engagement with the outer face of the grate bars 54. The louvers have a length substantially the width of the fuel distributors 18 (Fig. 2) so that there are five rows of louvers at the side of each of the

vertical grates 14. The louvers 68 are spaced vertically at such a distance and have such a width that they will support fuel running through the grate at its angle of repose and prevent the fuel from going beyond the louvers. The fuel passing through the grates may be incandescent and thus the grates will be embedded in a body of incandescent fuel and will be liable to be burned out. To prevent this, the louvers are cup-shaped and immediately above each longitudinal row of louvers at the side of the producer, is positioned a water pipe 70 by which water may be delivered to the louvers to quench the fuel and cool the grates. Water flowing on the fuel of the louvers will be converted into steam and the steam will be drawn through the grates by the induced draft operating the producer and thus tend to cool the fuel in contact with the grates. The steam entering the fuel columns will be converted into water gas.

Although the fuel collected in the louvers is cooled with water, the heat of the fuel columns will slowly burn the fuel so that the louvers will generally become filled with ash. The accumulation of ash on the louvers, especially when burning a non-coking coal, will tend to form ash inside of the grates so that it is desirable to keep the louvers as free as possible of ash to keep the grate bars from becoming clogged and thus cut down the ventilation of the fuel column. To remove ash collecting on the louvers, the louvers are pivotally mounted between vertical bars 72 which are connected at their upper ends to the I-beam 35 and at their lower ends to the channel beam 64 (Figs. 1, 2 and 6). Lugs 74 are formed on the lower side of the louvers which are connected by means of chains 76 to actuating rods 78. The upper ends of the rods 78 are connected by means of chains 80 with pulleys 82 which are fixed on horizontal shafts 84 journalled on the side of the I-beams 35 (Fig. 1). The front end of the shafts 84 extends outwardly beyond the front of the producer and are arranged to be rotated by means of hand-chains 86 which run over sprocket wheels 88 fixed on the outer end of the shaft. When the shaft 84 is rotated by the hand-chain 86, all of the louvers on one side of the producer will be simultaneously tilted to discharge ash against the outer face of the grates.

The ash discharged from the louvers is collected in a pair of hoppers 90 which are positioned along each side of the producer at the bottom of the vertical grates 14. The spout of the hoppers 90 is positioned directly over discharge openings 92 which are formed in box-beams 94 constituting a portion of the lower part of the structural frame-work. Since fuel or ash is discharged only periodically from the louvers, the openings 92 in

the box-beams are normally closed by covers 96 to prevent returned flue gases from escaping from the producer or to prevent air from being drawn into the producer. When ash, 5 fuel, or a mixture of ash and fuel is being collected from the louvers in the hoppers 90, the spouts of the hoppers are closed by means of gates 98 and when it is desired to discharge ash from the hoppers 90, the 10 covers 96 are removed and the gates 98 opened to allow ash to run down inside of the producer to be collected in the ash hoppers 34.

The inverted V-shaped grates 24 positioned in the mid portion of the producer act 15 to separate the lower portion of the fuel into two distinct columns and since the grates extend the entire length of the producer, they provide an enormous grate area 20 for supplying gases for controlling combustion to the mid portion of the fuel. The grates 24 (Fig. 1) consist of a series of bars 100 which are supported between an arch beam 102 and a foundation beam 104. The 25 grate bars 100 are provided with a notch 114 at their upper ends and with a beveled face 116 at their lower ends which cooperate respectively with flanges 118 on the lower edges of the arch beam and with a lug 120 formed on the upper face of the foundation beams. The notches 114 have sufficient depth 30 so that the bars 100 may be moved longitudinally to permit them to be moved over the lug 120 to be removed from the producer.

To prevent fuel from running through the 35 grates 24, louvers 122 having a construction similar to the construction of the louvers 68 are positioned in rows along the outer 40 face of the grates 24, there being one row of louvers for each section of the arch beam 102. The louvers 122 are pivotally mounted and are adapted to be rotated to discharge ash therefrom. To rotate the louvers, 45 chains are connected to lugs formed on the bottom of the louvers and pass over pulleys fixed on a shaft 128. The outer end of the shaft 128 extends outwardly beyond the front of the producer and is arranged to be rotated by means of a hand-chain 130 which 50 passes over a sprocket wheel 132 fixed on the outer end of the shaft. To quench fuel passing through the grate bars 100 into the 55 louvers 122, a series of water pipes 133 are positioned in front of the longitudinal rows of louvers and arranged to direct water upon fuel in the louvers.

The fuel discharged from the louvers 122 60 passes downwardly along the grates 24, across the inclined face of the beam 104, and falls upon a floor 134. The floor 134 is positioned adjacent the lower ends of the cooling shafts 26 and is supported at its opposite ends by beams 136 (Fig. 2) which span between box-beams 138. The box beams 138 65 extend from the front to the rear of the pro-

ducer parallel to the floor 134 and are supported on girders 140 (Figs. 1 and 2) which are positioned in the front and rear walls of the framework. Upon the box beams 138 are positioned refractory masonry walls 142 70 which support the foundation beams 104 of the grates 24. The side walls 142, grates 24 and floor 134 constitute a tunnel by which gas for controlling combustion may be supplied to the grates 24 and by which ash discharged from the louvers 122 may be removed from the producer. The front end of the tunnel is closed by ventilation doors 144 by which air may be admitted in regulated amounts to the tunnel to pass to the grates 80 24. The floor 134 consists of a series of inverted T-bars 146 which rest on the beam 136 and are spaced apart a distance equal to the length of brick, the space between the bars 146 being filled with brick 148. Instead of removing ash falling upon the floor 134 through the tunnel doors 144, it may be discharged through openings 150, formed in the floor by removing bricks 148 therefrom (Fig. 3), and collected in the hoppers 34. 90

After the fuel moves below the grates 14 and 24 and while it passes down through the shafts 26, the only ventilation given to the fuel is that which is admitted at the bottom of the shafts. The front side of the supporting beams 104 and the walls 142 (Figs. 1 and 3) are made of a refractory masonry construction and the steel frame structure opposite the walls 142 is lined with refractory construction to protect the same from 100 heat.

The reciprocating grates 28 for discharging carbonized fuel from the bottom of the fuel columns consist of a series of grate-bars 152 (Fig. 1). The grates 28 are secured to I-beams 158 and the I-beams 158 for each grate are bound together by transverse beams 160 to form a reciprocating frame. The portion of the beams 160 between the I-beams 158 are arranged to roll 110 upon rollers 162, which are loosely journaled on shafts 164 mounted between beams extending transversely of the producer. When the grates are supported in a central position below the combustion shafts 26, the 115 grates have sufficient width to support ash emerging from the shafts so that it will not run down from the shafts while the grates are stationary. At the time the grates are reciprocated the ash is discharged alternately at the sides of the grates. 120

The reciprocating motion of the grates 28 and the frame 158-160 is imparted by means of hydraulic engines 168 which are mounted on the front of the producer. The 125 pistons of the hydraulic engines 168 are connected by a rod 170 and the reciprocating motion of the rod 170 is imparted to a shaft 172 journaled longitudinally of the producer by means of a rocker-arm 174. The 130

- upper end of the arm 174 is fixed to the shaft 172 and a roller 175 is journalled in the lower end of the arm which engages collars 176 adjustably mounted on the rod 170.
- 5 To impart the motion of the shaft 172 to the grates 28, cables 178 are connected to the opposite ends of the beams 160 and pass over cam-arms 180 which are fixed on the shaft 172 immediately below the beams 160 (Fig. 1).
- 10 The cables 178 are securely attached to the cam-arms 180 and the oscillating movement of the cam-plates caused by the hydraulic engines imparts a reciprocating motion to the grates. The collars 176 on the piston rod 170 may be adjusted to vary the oscillating movement of the rocker-arm 174 and thus vary the reciprocating movement of the grates. By this arrangement the grates may reciprocate through a short or long distance either rapidly or slowly to give any desired rate of discharge of fuel and thus control the rate of passage of fuel through the producer. If the fuel or ash tends to clog on the grates 28, they may be easily cleared by means of bars which can be inserted through the doors 182 extending along the entire length of the grates (Fig. 2).

The flue gases entering the producer 20 through the tube 30 may be positively forced through the tube by means of a blower or fan and may be controlled by means of a valve 184. The lower portion of the producer is closed so that the only path for the 25 passage of flue gases is upwardly through the grates 28 and into the cooling shafts 26. In this way the carbon dioxide of the flue gases may be used to control the temperature of combustion in the shafts 26. In 30 some cases, however, it may be desirable to admit flue gases through the V-grates 24 and to accomplish this bricks 148 may be removed from the floor 134 below the V-grates to provide openings such as 150 for 35 flue gases to pass up into the grates 24. The size of the openings 150, however, may be accurately controlled or easily closed by plates 151 to control the passage of flue gases through the grates 24. The main air 40 supply for supporting combustion which passes through the grates 24 is admitted through the ventilation doors 144.

In view of the above description, it will be seen that the air for supporting and controlling combustion may all be drawn through the producer by induced draft and pass through the vertical grates 14, the V-grates 24, and the discharge grates 28. Likewise the flue gases for controlling combustion 45 may all be drawn through the producer by induced draft and pass through the V-grates 24 and the discharge grates 28. This grate area is exceedingly large in comparison with the grate areas of the usual producers and furnaces and thus allows a very large

amount of fuel to be consumed in making gas in relation to the floor area of the producer. Further, this arrangement of the grates supports the fuel columns so that all parts of it may be properly supplied with air or returned flue products.

In some of the claims the word "upright" is used to define the arrangement of the grates 14 and 24. By the word "upright" it is intended to mean any grates which are supported in a vertical position or in any inclined position at which the fuel on the grates will flow by gravity.

The preferred form of the invention having been thus described, what is claimed as new is:

1. A process of making producer gas, comprising passing fuel in a column downwardly through a shaft, introducing air under induced draft into the major portion of the upright sides of said column to promote gas making reactions therein, controlling the air supply to maintain the highest gas making temperatures in the upper portion of the column, removing producer gas formed adjacent the top of the shaft, introducing flue gases for controlling combustion into the lower part of the fuel column, and controlling the movement of flue gases upwardly through the fuel column to cause a lowering of temperature in the fuel as it advances below the mid-portion of said column.

2. A process of making producer gas, comprising passing fuel in a column downwardly through a shaft, drawing air under induced draft into said column over a substantial portion of its upright lateral area to promote gas making reactions therein, removing the producer gas formed adjacent the top of the shaft, maintaining the highest combustion temperatures in the upper part of said column, introducing flue gas into the lower portion of said column to maintain the temperature therein below the fusion point of the ash, and decreasing the cross-sectional area of the fuel column as it advances downwardly to progressively retard the movement of flue gases and air therethrough.

3. A process of making producer gas, comprising passing fuel in a column downwardly through a shaft, heating the fuel at the top of the column by radiation, introducing air into a major portion of the longitudinal sides of said column to promote gas making reactions therein, removing the producer gas formed adjacent the top of the shaft, controlling the air supply to maintain the highest gas making temperatures in the upper portion of the column, supplying air at a reduced rate to the fuel column below the mid-portion to maintain a combustion temperature therein below the fusion point of the ash, supplying flue gases for controlling combustion throughout a major portion of

the lower part of the fuel column and admitting sufficient oxygen with said flue gases to maintain a slow combustion in the lower portion of said column.

- 5 4. A process of making producer gas, comprising passing fuel in a column through a shaft, introducing air under induced draft into the upright sides of said column to maintain high gas making temperatures in
10 the top portion of said column and progressively lower temperatures of combustion in the fuel column as it advances downwardly, removing producer gas formed adjacent the top of the shaft, reducing the air supply to
15 the lower portion of the fuel column, and passing gases for controlling combustion upwardly therethrough in amounts sufficient to prevent the formation of clinker in the zone of the fuel column where the ash attains a
20 sufficient percentage for clinker formation.

5. A process of making producer gas, comprising passing fuel substantially continuously in a column downwardly through a shaft, admitting air under induced draft to a major portion of the longitudinal sides 25 of the column to promote gas making reactions therein, controlling the air supply so as to maintain the highest combustion temperatures in the upper portion of the fuel column, removing producer gas formed adjacent the top of the shaft, cooling the fuel in the lower portion of the column by promoting endothermic dissociation of flue gases in direct contact therewith, and controlling the rate of advancement of fuel through 30 the shaft and the volume and character of gases passed counter-currently thereto.

In testimony whereof I affix my signature.

HENRY L. DOHERTY.
